METHOD AND APPARATUS FOR ANNEALING

Ralph M. Parsons, Mount Vernon, Ohio, assignor
to The Ralph M. Parsons Company, Mount
Vernon, Ohio, a corporation of Delaware

Application March 2, 1935, Serial No. 8,993

4 Claims. (Cl. 148—13)

This invention relates to annealing and more particularly to a process and apparatus for annealing large hollow articles such as pipes or vessels.

5 An object of this invention is to provide simplified and improved means for annealing large hollow articles.

Another object is to provide relatively cheap equipment for annealing such articles.

10 Another object is to provide for annealing such articles without use of a large heating chamber.

A more specific object is to provide an improved process for the manufacture of large pressure vessels for oil refineries.

15 Various other objects will be apparent as the nature of the invention is more fully disclosed.

In accordance with this invention the article to be annealed, which may comprise a heavy pressure vessel of the type used in oil refineries, is

20 heat insulated on the outside and hot gases are passed therethrough at a rate to heat the vessel to the temperature desired for annealing. Thereafter the temperature and flow of the gases are controlled so as to maintain the temperature

25 time characteristics required for annealing. The hot gases may comprise air, furnace gases, superheated steam, hot oil vapors or the like, depending upon the availability. The vessel may be insulated by being embedded in the earth or

30 in a pit or receiver containing any natural insulating material such as earth, clay, Zonolite, mica, limestone, or the like.

Various novel features which are believed to be characteristic of this invention will be more particularly pointed out in the claims appended hereto, but the invention itself may be better understood by referring to the following description taken in connection with the accompanying drawing in which one embodiment thereof has 40 been set forth for purposes of illustration.

In the drawing, the figure is a diagrammatic representation of one means for carrying out the invention.

Referring to the drawing more in detail the 45 invention is shown as applied to the annealing of a large pressure vessel 10, such as a reaction chamber for an oil cracking plant. Such a vessel may be fabricated by spot welding which produces local regions of varying stress which must 50 be relieved before the vessel is placed in use. Stress relieving requires a temperature-time characteristic well known in the annealing art and consisting in general of heating the article to a predetermined temperature, for example 55 1600° F., and cooling through a given temperature

range at a definite rate. In some instances reheating and recooling may be required. The present invention provides for obtaining whatever temperature-time characteristics may be required in accordance with general annealing practice and is not to be limited to any specific example thereof. 5

A reaction chamber may be, for example, forty feet long and five feet in diameter. Hence, if the annealing were to be accomplished in a furnace or heating chamber, a large and expensive construction would be required. In accordance with the present invention however the necessity for such a furnace is eliminated. 10

More specifically, the vessel 10 is heat insulated 15 on the outside by means of an insulating material 11 such as, earth, clay, Zonolite, limestone, mica or the like, preferably by a material that is locally available and may be cheaply obtained. In parts of Montana, for example, Zonolite is readily obtained and may be conveniently used for this purpose. This material has a mica base and may be pumped or transported as a flaky mass. A receiver, such as a pit 12, may be partly filled with this material, the vessel 10 20 placed therein and further quantities of the material may be added until the outer surface of the vessel 10 is covered to the desired extent. If no special insulating material is locally available the vessel 10 to be annealed may be buried in the 25 ground. The efficiency of the heat insulation is not of great importance as only a few articles 30 will be treated at any one plant and fuel will be a relatively small item.

Pipes 14 and 15 may be connected to the two 35 ends of the vessel 10, as by couplings 16 which may be secured to the vessel as by bolts 17 and may be attached to the pipes 14 and 15 by flanges 19 and bolts 20. The pipe 14 may lead to a source of hot gases such as a furnace 25 having a burner 26 provided with a fuel supply line 27 and an air supply line 28. The furnace may be of any convenient construction. If a furnace is included in the plant equipment, such for example as the cracking furnace of an oil cracking plant, the 40 same may be used for this purpose. If a source of superheated steam is available the steam may be supplied to the pipe 14 in the same manner. 45

In the embodiment disclosed the pipe 14 constitutes the exhaust duct for the combustion gases 50 from the furnace 25. The pipe 15 may constitute a discharge means for the gases after they have served their purpose in heating the vessel 10.

In order to obtain a more efficient heat transfer from the gases to the vessel 10 recirculation 55

may be employed. For this purpose a pipe 30 is provided which interconnects the pipes 14 and 15 at points near the vessel 10. The pipe 30 may contain a source of pressure such as a blower 31 adapted to produce circulation therein in a direction from the pipe 15 and toward the pipe 14. The pipe 30 may join the pipe 14 at an angle so as to discharge gases toward the vessel 10 whereby circulation of gases from the furnace 25 5 to the vessel 10 is induced in the pipe 14. A baffle 32 may assist in obtaining this circulation. The relative quantity of gases recirculated through the pipe 30 may be controlled by a damper 33 located therein, preferably ahead of 15 the blower 31. The flow of gases from the furnace 25 may be controlled by a damper 34 in the pipe 14. A suitable temperature indicator such as a pyrometer 35 may be located in the pipe 14 at a point near the vessel 10 to show the temperature 20 obtaining in the vessel.

In the operation of this invention the vessel 10 is placed in the bed of insulating material 11 in a pit 12 or the like, pipes 14 and 15 are connected thereto, and the burner 26 is regulated to 25 produce the desired combustion in the furnace 25. The hot gases of combustion pass from the furnace 25, through the pipe 14 to the vessel 10, thence out through the pipe 15. Recirculation is obtained by regulating the blower 31 and the 30 damper 33 in the pipe 30. By suitable control of the rate of combustion, the recirculation and the flow of gases from the furnace to the vessel 10, the temperature may be raised to any value desired. Thereafter the rate of cooling may be 35 controlled in a similar manner. Obviously if no heat is required during certain cooling stages, the flow of gases from the furnace may be entirely interrupted.

This process provides economical means for 40 annealing large articles at the plant. This renders it possible to construct such articles in the field and anneal them as required, as distinguished from manufacturing the articles at a point equipped with large furnaces and other 45 annealing equipment.

The vessel 10 is shown by way of illustration only. The method may be employed for pipes, and other hollow articles with equal advantage. The invention is particularly useful for annealing 50 bent pipes of large dimensions which would require a large heating chamber if the pipe were to be annealed by heat externally applied.

It is obvious that recirculation may be omitted if the proper temperatures are otherwise obtained. The gases employed should be such as not to attack the metal of the vessel. In some cases air may be employed, or in the case of pipes a liquid such as oil may prove satisfactory. Superheated steam may be used when available. 55 In general, any fluid may be used which is capable 60

of transferring its heat to the walls of the article.

Certain specific terms have been used herein for convenience but they are to be interpreted as broadly as the art will permit. Although a specific embodiment of the invention has been set forth, various changes, modifications and adaptations will readily occur to a person skilled in the art. The invention is to be limited only in accordance with the following claims when interpreted in view of the prior art. 10

What is claimed is:

1. Apparatus of the class described comprising a source of hot gases, a pipe adapted to lead said gases from said source to an article to be annealed, means to control the flow of said gases 15 in said pipe, a second pipe adapted to discharge hot gases that have passed through said article, a third pipe interconnecting said first pipes, blower means therein to cause recirculation of gases through said article, means to control the 20 quantities of gases thus recirculated, and means whereby flow of said recirculated gases induces circulation of gases from said source to said article.

2. The process of annealing a large hollow 25 article without using an annealing oven which comprises sealing the article against escape of gases therefrom, heat insulating the outside thereof, introducing a hot fluid into said article, causing the fluid to pass entirely through said 30 article for uniformly heating the walls thereof and then to be discharged therefrom, and obtaining the temperature-time characteristic required for annealing by controlling the temperature and rate of flow of said fluid. 35

3. The process of annealing a large hollow article without using an annealing oven which comprises sealing the article against escape of gases therefrom, heat insulating the outside 40 thereof, introducing a hot fluid into said article, causing the fluid to pass entirely through said article for uniformly heating the walls thereof and then to be discharged therefrom, recirculating controlled portions of said fluid to increase the heat transfer therefrom and obtaining the 45 temperature-time characteristic required for annealing by controlling the temperature and rate of flow of said fluid.

4. The process of annealing a large hollow article without using an annealing oven which 50 comprises sealing the article against escape of gases therefrom, embedding the article in heat insulating material, introducing a hot fluid into said article, causing the fluid to pass entirely through said article for uniformly heating the 55 walls thereof and then to be discharged therefrom, and obtaining the temperature-time characteristic required for annealing by controlling the temperature and rate of flow of said fluid.
